SLUG CASTING MACHINE

Anthony J. Stouges, Queens' Village, N. Y., assignor to Mergenthaler Linotype Company, a corporation of New York

Original application June 19, 1931, Serial No. 545,398. Divided and this application January 31, 1933, Serial No. 654,558. In Great Britain January 25, 1932

10 Claims. (Cl. 199—50)

This invention is directed to an improved automatic slug casting machine, and particularly to a machine of the type shown in my co-pending application, Serial No. 545,398, filed June 19th, 1931, 5 of which the instant application is a division.

The machine is adapted to handle not only the regular linotype matrices, (in order that the vast number of outstanding matrix fonts may be utilized, if desired); but in addition matrices of special form which could not be handled in the regular commercial machines, and which are intended for hand composition only.

In the use of the machine, the matrices are composed in line and justified in a hand stick or holder which then is placed in the machine and the composed line thereafter presented automatically to the casting mechanism. During each cycle of operation, a slug is cast in the selected mold, ejected therefrom, trimmed, and finally stacked in a galley arranged conveniently at the front of the machine.

The hand composed line (herein of maximum length) is transferred to the elevator or transporter which positions it between a pair of vise jaws. The vise jaws are movable, the left-hand jaw being moved toward the opposing or right-hand jaw from a normal to a definite predetermined position, thus to position the line of matrices in proper longitudinal registry with the mold slot. The right-hand jaw has a spring arranged behind it, permitting it to yield under the thrust of the left-hand jaw through the composed matrix line, this spring offering the sole resistance required for the lock-up of the line. 35 The yielding movement of the right-hand jaw actuates a pump stop device which permits the slug to be cast from the line and the normal cycle of operation to proceed.

In the accompanying drawing, the improvements have been shown merely in preferred form and by way of example, and obviously many changes and variations may be made therein and in their mode of adaptation and still be comprised within the scope of the invention. It should, therefore, be understood that the invention is not limited to any specific form or embodiment, except insofar as such limitations are specified in the claims.

Referring to the drawing:

Fig. 1 is a side elevation of the improved machine, showing the parts in their normal position of rest;

Fig. 2 is a plan view partly in section of the vise cap, showing the line clamping jaws in their normal or inactive position;

Fig. 3 is a front view showing a matrix line locked between the clamping jaws, the vise frame being indicated by broken lines; and

Fig. 4 is a partial plan view of the pump stop lever, showing the manner in which it is operated by the movement of the clamping jaws.

The disc A is rotatably mounted, as usual, on a fore-and-aft mold slide (not shown), and is equipped, in the present instance, with a plurality of slotted molds, any selected one of which may

be brought into use by the rotary adjustment of the disc as effected in the usual way by means of the driving pinion A².

As the machine is started by the engagement of the main driving clutch (not shown), the cam shaft R is rotated slowly and the mold disc or carrier A is given a quarter turn in an anti-clockwise direction (looking from the front of the machine) to locate the selected mold L² in the casting position.

The elevator or transporter B then descends to position a line of matrices X (previously delivered thereto) in front of the active mold, where the line is held between the clamping jaws C¹, C² mounted in the fixed vertically disposed vise frame D.

The mold slide is now moved forward to bring the active mold up against the matrix line, which thereby closes the mold slot at the front, and the metal pot E is likewise advanced

from its normal position behind the disc A to bring the mouthpiece E¹ thereof up against the back of the mold, thereby closing the mold slot at the rear.

The descent of the pot plungers immediately follows, and molten metal is ejected from the pot into the mold to produce the cast slug.

As the cycle of operation proceeds and the cam shaft R continues to revolve, the pot plungers are raised, the metal pot E and the mold slide are caused to recede, and the disc A is given

a three-quarter turn in the same direction as before to carry the mold with the contained slug to a vertical position, whence it is ejected and trimmed.

Before the mold disc A is advanced preparatory to the casting operation, and irrespective of the level at which the transporter B is arrested, the matrix line (which has a blank matrix X¹ at each end to close the deep routing notches of the end letter matrices) is clamped tightly between the vise jaws C¹, C² and positioned there-

by endwise so that the inner faces of the blank matrices register properly with the end walls of the mold slot. This operation is effected by a vertical reciprocating wedge bar M through the medium of a short horizontal slide rod C³, against

which the left-hand jaw C¹ abuts.

Before the mold disc A is advanced preparatory to the casting operation, and irrespective of the level at which the transporter B is arrested, the matrix line (which has a blank matrix X¹ at each end to close the deep routing notches of the end letter matrices) is clamped tightly between the vise jaws C¹, C² and positioned there-

by endwise so that the inner faces of the blank matrices register properly with the end walls of the mold slot. This operation is effected by a vertical reciprocating wedge bar M through the medium of a short horizontal slide rod C³, against

which the left-hand jaw C¹ abuts.

The rod C³ is mounted in fixed bearings D¹¹, D¹² and is provided between said bearings with a rigid block or collar C⁴, and the bar M, located to the left of the collar C⁴, is formed with an elongated slot m through which the rod C³ extends. The side face of the bar M opposed to the bearing D¹¹ is straight or vertical, while the other face, that opposed to the block C⁴, is inclined upwardly to accord with the similarly inclined face of said block. As shown in Fig. 3, the block C⁴ is held resiliently engaged with the bar M by a compression spring C⁵ seated in the bearing D¹², and serving also to hold the bar against the bearing D¹¹. The jaw C¹, moreover, is provided with a compression spring C⁶ mounted in a block D¹³ secured to the vise frame D, and which holds the jaw resiliently against the rod C³.

As the parts are thus arranged, when the bar M is raised, the rod C³ and jaw C¹ are forced positively thereby to the right or toward the opposing jaw C², whereas when the bar is lowered, the rod C³ and jaw C¹ are forced to the left or returned to their original positions by their respective springs C⁵ and C⁶.

The bar M is operated from the cam shaft R by means of a fore-and-aft lever M¹, which is connected to the lower end of the bar by an intermediate link M². The upward movement of the bar M (in the present instance a positive one), is limited by a stop screw m¹ which is arranged in the vertical path of the lever M¹, and hence the jaw C¹ is always moved a definite distance by the bar M so as to locate the end matrices of a properly composed line positioned between the two clamping jaws in registry with the end walls of the mold slot.

If the line is of proper length, the movement of the left-hand jaw C¹ will be imparted by the line to the right-hand jaw C², which, under such circumstances, is adapted to yield toward the right against the tension of a spring C⁷ which normally holds it toward the left against a fixed stop D¹⁴, and which offers the resistance required for the lock-up of the line. The spring C⁷ is supported on a horizontal rod D¹⁵ rigidly mounted in a bracket D¹⁶ fastened to the vise frame D. In yielding, the jaw C² is adapted to actuate the safety pump stop lever N common to the commercial linotype machines, and which, when actuated, permits the cycle of operation to proceed, the active mold being moved up against the matrix line and the pot plungers E⁵ being allowed to descend by action of the spring E² hereinbefore mentioned. If the pump stop lever N is not actuated by the yielding of the jaw C², the casting operation can not take place.

Although it is believed the operation of the mechanism will be readily understood from the foregoing description, it might be here stated that the line of matrices being hand composed, is justified in the stick or holder, and delivered in such condition by the transporter B between the clamping jaws C¹, C², which normally are spaced apart a distance somewhat larger than the length of the line for this purpose. The left hand jaw is then actuated toward the right hand jaw to lock up the line for casting, the necessary clamping pressure being furnished by the yielding right hand jaw C² as motion is imparted to it by the left hand jaw C¹, through the intervening line as it is moved to place the inner faces of the end blank matrices in registry with the mold slot.

Having thus described my invention, what I claim is:

1. In a slug casting machine, adapted to be equipped with a non-expansible composed matrix line of a given length, the combination of a supporting frame, right and left hand clamping jaws mounted for horizontal movement in said frame, a transporter for positioning said matrix line between said jaws, positive means for moving the left hand jaw toward the opposing jaw from a normal to a definite predetermined position, said means having a range of movement sufficient to reduce the distance between the jaws to less than the length of said matrix line, a line-clamping spring arranged behind the right hand jaw to permit it to yield under the thrust of the left hand jaw through the composed matrix line, and a fixed stop to limit the yielding movement of the right hand jaw.

2. A combination as in claim 1, including a spring for returning the left hand jaw to its normal position, and characterized by the fact that the spring associated with the right hand jaw offers the sole resistance required for the justification of the line.

3. In a slug casting machine, the combination of a supporting frame, right and left hand clamping jaws mounted for horizontal movement in said frame, a transporter for positioning composed matrix lines of a given length between said jaws, a vertically reciprocating wedge bar adapted in its upward movement to shift the left hand jaw to active position against the line, means for operating the wedge bar, and a fixed stop for limiting the upward movement of said bar so as to locate the left hand jaw definitely in its active position.

4. A combination as in claim 1, including a pump stop device actuated by the yielding movement of the right hand jaw.

5. In a slug casting machine, adapted to be equipped with a non-expansible composed matrix line of a given length, the combination of a supporting frame, right and left hand clamping jaws mounted in said frame and normally spaced apart for a distance corresponding approximately to the length of said matrix line, means for moving one of the jaws toward the other and having a range of movement sufficient to reduce the distance between the jaws to less than the length of said matrix line, a transporter for positioning the matrix line between said jaws, and a line-clamping spring for moving one of said jaws against the line to exert a clamping pressure thereon.

6. In a slug casting machine, adapted to be equipped with a non-expansible composed matrix line of a given length, the combination of a supporting frame, right and left hand clamping jaws mounted in said frame and normally spaced apart for a distance corresponding approximately to the length of said matrix line, a transporter for positioning the matrix line between said jaws, means for moving one of the jaws toward the other and having a range of movement sufficient to reduce the distance between the jaws to less than the length of said matrix line, a line-clamping spring for moving one of said jaws against the line to exert a clamping pressure thereon, and means comprising a fixed stop for limiting the movement of said jaw to position the line in predetermined relation with the mold.

7. In a slug casting machine, the combination of a supporting frame, right and left hand clamping jaws mounted in said frame and spaced apart

- 5 a predetermined distance to receive lines of a given length, a transporter for positioning composed matrix lines approximately of such length between said jaws, a vertically reciprocable wedge bar adapted in its upward movement to shift one of said jaws to exert clamping pressure against the line, means for operating the wedge bar, and a fixed stop for limiting the upward movement of said bar to fix the active position of said 10 jaw so as to position the line in predetermined relation with the mold.
8. In a slug casting machine, the combination of a supporting frame, right and left hand clamping jaws mounted for horizontal movement in 15 said frame, a transporter for positioning composed matrix lines of a given length between said jaws, a vertically reciprocatory wedge bar adapted in its upward movement to shift the left hand jaw to active position against the 20 line, means for operating the wedge bar, a fixed stop for limiting the upward movement of said bar so as to locate the left hand jaw definitely in its active position, said right hand jaw being adapted to yield under the thrust of the left hand 25 jaw through the composed matrix line, and a pump stop device actuated by the yielding movement of the right hand jaw.
9. In a slug casting machine, adapted to be equipped with a non-expansive composed matrix line of a given length, the combination of a supporting frame, right and left-hand clamping jaws mounted in said frame and normally spaced apart for a distance corresponding approximately to the length of said matrix line, both jaws normally occupying a position to the left of their active positions, means for moving the left-hand jaw toward the right to its active position and 10 through the composed line for moving the right-hand jaw toward the right to its active position, said means having a range of movement sufficient to reduce the distance between the jaws to less than the length of said matrix line, and 15 a line-clamping spring arranged behind the right-hand jaw and resisting but permitting its rightward movement; whereby during casting the jaws are properly positioned and the composed line clamped under pressure between them. 20
10. A combination as in claim 9, characterized by the fact that the means for moving the left-hand jaw act only to move it toward the right and include a spring for restoring the jaw to its normal position to the left after casting. 25
